COMBINED COIN AND ARTICLE HOLDER

Filed April 4, 1930

Fig. 1.

Fig. 2.

A hand-drawn diagram showing a cross-section of a finger-like structure. The structure is bounded by a wavy line at the top and a straight line at the bottom. Inside, there is a central vertical column with horizontal cross-hatching. The top of this column is labeled 'H' and the bottom is labeled 'G'.

ATTORNEY

UNITED STATES PATENT OFFICE

JAMES E. HUGHES, OF DIXON, MISSOURI

COMBINED COIN AND ARTICLE HOLDER

Application filed April 4, 1930. Serial No. 441,677.

This invention relates to a certain new and useful improvement in combined coin and article-holders and has for its object the provision of a simple, inexpensive, durable, compact, and easily portable and conveniently operable device of the type stated especially, though not exclusively, adapted for facilitating the collection of rural mail and the like.

10 And with the above and other objects in view, my invention resides in the novel features of form, construction, arrangement, and combination of parts hereinafter described and pointed out in the claims.

15 In the accompanying drawing,—

Figure 1 illustrates a combined coin and article-holder of my invention as operatively disposed as in a rural mail-box for removal and manipulation;

20 Figure 2 is an enlarged elevational view of the combined coin and article-holder;

Figure 3 is an enlarged fragmental edge view of the combined coin and article-holder; and

25 Figure 4 is a transverse sectional view taken approximately on the line 4—4, Figure 2.

Referring now more in detail and by reference characters to the drawing, which illustrates a preferred embodiment of my invention, the device includes a main or body-member or wall A preferably constructed of sheet metal and of oblong-rectangular configuration, wall A being also preferably strengthened or re-enforced by a lateral

35 flange a disposed along a lengthwise margin thereof. At its one or rear margin, wall A is also preferably flanged laterally, as at b, and riveted or otherwise rigidly fixed flatwise to and upon the flange b is an upwardly projecting end-wall B preferably flanged outwardly at its upper margin, as at c.

Disposed upon the wall A adjacent its opposite or forward end, is a box-shaped receptacle C of suitable dimensions for housing coins and the like, the receptacle C being constructed preferably of a suitable section of sheet metal bent or otherwise formed to the desired configuration shown and riveted or otherwise marginally fixed, as at 1, 1, to the wall A. The receptacle C is open or other-

wise provided with a coin-receiving opening at its one or forward end, as at 2, its wall being preferably cut-away or otherwise apertured, as at 3, to visually expose the deposited contents of the receptacle.

Riveted or otherwise fixed, as at 4, to the wall A and extending endwise rearwardly thereof and over the wall-flange c, to which it is also preferably riveted, as at 5, is an arm D; and pivoted, as at 6, to the wall flange c, is a second arm E, a coiled spring F being suitably mounted between the rear ends of the arms D, E, for yieldingly retaining the arm E in its full normal spaced relation from the arm D.

The arm E is lengthwise continued, as at e, to extend longitudinally approximately throughout the length of the wall A and at the forward extremity of its continuation e is further extended laterally to include an end-portion e' adapted to project over or across and provide a removable closure for the said coin-opening or open side 2 of the coin-receptacle C.

The arms D and E are preferably formed and shaped of sheet metal, and suitably fixed at an end, as at 7, to the arm-continuation e, is a somewhat spring or resilient preferably sheet-metal jaw G preferably of the shape or contour best shown in Figure 4 for clamping co-operation with a relatively stationary sheet metal jaw H projecting laterally from, and fixed, as at 8, to, the wall A, as best seen in Figure 4.

My new combined coin and article-holder is particularly, as I have stated, adapted to facilitate rural mail collections, and in use and operation, I might briefly explain, the farmer or other person will, by finger-manipulation of the co-operating arms D, E compress the spring F to simultaneously open the receptacle C and space the jaws G, H. He will then dispose on the jaw H the letter or other article J that he desires to mail and deposit in the receptacle C the estimated funds to cover the cost of postage thereof. He will then release or remove compressing pressure on the spring F, when the arm E will yieldingly take its normal position, the letter or article J then being gripped by and

between the jaws G, H, and said funds being removably retained in the receptacle C by the closure e' such deposited funds being visually exposed through the aperture 3, as best seen in Figure 2. The device and its so gripped article J and deposited coin or coins may then be conveniently deposited to rest obliquely, with the flange b as a support, within the mail-box 12 for convenient gripping at the rear ends of its arms and for convenient reverse manipulation by the carrier in removing the gripper article and contained coin or coins, the emptied device being then replaced in the box K for repeated use.

The device as a whole may be cheaply and economically manufactured, is easily portable and of convenient size for convenient manual manipulation, and is exceedingly efficient in the performance of its intended functions. It will be understood, of course, that the receptacle C may equally well be employed to contain postage stamps and the like, and that changes and modifications in the form, construction, arrangement, and combination of the several parts of the device may be made and substituted for those herein shown and described without departing from the nature and principle of my invention.

Having thus described my invention, what I claim and desire to secure by Letters Patent is:

1. A combined holder for coins, articles, and the like adapted for manual disposition in a mail-box or the like, the same including a body-member, a receptacle having a receiving-opening, a fixed jaw on the body-member, a closure-member for removably closing said opening, a movable jaw for article gripping co-operation with the first jaw, and means for actuating the closure-member and the second jaw.

2. A combined holder for coins, articles, and the like adapted for manual disposition in a mail-box or the like, the same including a body-member, a receptacle having a receiving, a fixed jaw on the body-member, a closure-member for removably closing said opening, a movable jaw for article gripping co-operation with the first jaw, and means for simultaneously actuating the closure-member and the second jaw.

3. A combined holder for coins, articles, and the like adapted for manual disposition in a mail-box or the like, the same including a body-member, a receptacle having a receiving opening, a fixed jaw on the body-member, a closure-member for removably closing said opening, a movable jaw for article-gripping co-operation with the first jaw, and means including an arm pivoted on the body-member for simultaneously swingably actuating the closure-member and the second jaw.

4. A combined holder for coins, articles,

and the like adapted for manual disposition in a mail-box or the like, the same including a body-member, a first arm fixed on the body-member, a receptacle having a receiving opening, a fixed jaw on the body-member, a closure-member for removably closing said opening, a movable jaw for article-gripping co-operation with the first jaw, means including a second arm pivoted on the body-member for simultaneously swingably actuating the closure-member and the second jaw, and a coiled spring disposed intermediate said arms for yieldingly retaining said closure-member and second jaw respectively in receptacle-closing and article-gripping positions.

5. A combined holder for coins, articles, and the like adapted for manual disposition in a mail-box or the like, the same including a sheet metal rectangular-oblong body-wall, a box-like sheet-metal receptacle fixed on the wall and having a receiving-opening in the wall thereof, a longitudinally disposed arm fixed to and projecting rearwardly of the body-wall, a sheet metal jaw fixed to and projecting laterally from the body-wall, a closure-member for said opening, a movable sheet-metal jaw for article-gripping co-operation with the first jaw, means including a second arm pivoted on the body-wall for simultaneously swingably actuating the closure-member and the second jaw, and a coiled spring disposed intermediate said arms for yieldingly retaining said closure-member and second jaw respectively in receptacle-closing and article-gripping positions.

In testimony whereof, I have signed my name to this specification.

JAMES E. HUGHES.
